UNITED STATES PATENT OFFICE

163,118

HOLDER FOR USE IN ABRASIVE
OPERATIONS

Arthur R. Isler, Warren, Ohio

Application March 29, 1949, Serial No. 1,697

Term of patent 3½ years
(Cl. D37—1)

To all whom it may concern:

Be it known that I, Arthur R. Isler, a citizen of the United States, residing at Warren, in the county of Trumbull and the State of Ohio, have invented a new, original, and ornamental Design for a Holder for Use in Abrasive Operations, of which the following is a specification, reference being had to the accompanying drawing, forming a part thereof.

In the drawing:

Figure 1 is a perspective view of a holder for use in abrasive operations, showing my new design,

Figure 2 is a side elevational view of the same, drawn to a smaller scale, and

Figure 3 is a top plan view of Figure 2.

The dominant features of my design reside in those portions shown in full lines.

I claim:

The ornamental design for a holder for use in abrasive operations, substantially as shown and described.

ARTHUR R. ISLER.
